United States Patent

Des. 239,553
Patented Apr. 13, 1976

239,553

TOY TRUCK

Jack L. Breneman, Orchard Park, and Jeffrey T. Samson,
East Aurora, N.Y., assignors to The Quaker Oats Company,
Chicago, Ill.

Filed Aug. 5, 1974, Ser. No. 494,626

Term of patent 14 years

Int. Cl. D21—01
U.S. Cl. D34—15 AJ

FIG. 1

FIG. 2

FIG. 3

FIG. 4

FIG. 5

FIG. 1 is a front perspective view of a toy truck showing our new design;

FIG. 2 is a left-side elevational view thereof shown on an enlarged scale;

FIG. 3 is a front elevational view thereof;

FIG. 4 is a rear elevational view thereof; and

FIG. 5 is a top plan view thereof.

The tire lugs fragmentarily shown in FIG. 1 are continuous over the surface of the tire members.

We claim:

The ornamental design for a toy truck, substantially as shown and described.
